UNITED STATES PATENT OFFICE.

GEORGE HARDY, OF LAWRENCE, MASSACHUSETTS.

CAR-COUPING.

SPECIFICATION forming part of Letters Patent No. 441,410, dated November 25, 1890.

Application filed September 12, 1890. Serial No. 364,724. (No model.)

To all whom it may concern:

Be it known that I, GEORGE HARDY, of Lawrence, in the county of Essex, State of Massachusetts, have invented certain new and useful Improvements in Car-Couplings, of which the following is a description sufficiently full, clear, and exact to enable any person skilled in the art or science to which said invention appertains to make and use the same, reference being had to the accompanying drawings, forming part of this specification, in which—

Figure 1 is an end view showing a portion of a car provided with my improved coupling; Fig. 2, a vertical transverse section showing the method of mounting the draw-bar, and Fig. 3 an elevation showing the coupler-heads locked.

Like letters and figures of reference indicate corresponding parts in the different figures of the drawings.

My invention relates to automatic car-couplers; and it consists in certain novel features, hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the body of the car, which is of the ordinary form and construction, and B the draw-bar. The inner end of the draw-bar is cushioned by a spring d, mounted in a box f in the usual manner. A block g is secured centrally to the end of the car, and the draw-bar is fitted to slide longitudinally therein. Said draw-bar is provided with a longitudinal spline h, which works in an arc-shaped recess in the block g and limits the rotation of said bar.

A torsion-spring j is wound around the draw-bar B and has one end secured thereto at k. A sleeve m is mounted on the draw-bar at the rear of the block g, and a lever-arm p is secured to said sleeve. A chain q has one end secured to said lever and passes over a pulley r on the car-body. From thence it passes to the top of said car, where it is provided with a ring or handle t. The chain v

is secured to the chain q, and is provided with a ring w, suspended on a hook x at the bottom of the car. A lever 15 projects downward from the sleeve m, and a chain 16 leads therefrom to the opposite side of the car, where it is provided with a handle or ring 17.

The draw-bars B are provided with a head 25, projecting at right angles to the body of said bar. The outer edge of said head is beveled rearwardly and laterally at 26.

In the use of my improvement when the cars come together the beveled edges of the heads 25 of the draw-bars engage. This causes said bars to rotate slightly, winding up the springs j. As the cars come closer together, the heads 25 pass each other, and when out of contact are quickly thrown inward by the action of said springs, overlapping each other, as shown in Fig. 3, and securely coupling the cars together. By means of the levers p 15 and chains 16 q the draw-bars B may readily be rotated from the side or top of the car sufficiently to disengage the draw-bar heads 25 and uncouple the cars when desired.

Having thus explained my invention, what I claim is—

1. In a car-coupling, the combination of a spring-cushioned draw-bar provided with a beveled laterally-projecting draw-head and with a longitudinal spline, a fixed block attached to the car-body, provided with a bearing for said draw-bar and with an arc-shaped recess, in which said spline has a limited oscillating movement, a torsional spring connected with said draw-bar, a sleeve on said draw-bar provided with a longitudinal groove for receiving said spline, and a laterally-projecting arm attached to said sleeve for oscillating said sleeve and bar.

2. In a car-coupling, the combination of a spring-cushioned draw-bar provided with a beveled laterally-projecting draw-head and with a longitudinal spline, a fixed block attached to the car-body, provided with a bearing for said draw-bar and with an arc-shaped recess, in which said spline has a limited oscillating movement, a torsional spring connected with said draw-bar, a sleeve on said draw-bar provided with a longitudinal groove for receiving said spline, a laterally-projecting arm attached to said sleeve for oscillating

said sleeve and bar, and a chain connected to said arm for actuating it.

3. In a car-coupling, the combination of a
5 beveled laterally-projecting draw-head and
with a longitudinal spline, a fixed block at-
tached to the car-body, provided with a bear-
ing for said draw-bar and with an arc-shaped
recess, in which said spline has a limited os-
cillating movement, a torsional spring con-
nected with said draw-bar, a sleeve on said
draw-bar provided with a longitudinal groove
for receiving said spline, arms projecting lat-
erally from said sleeve in opposite directions,
10 a chain connected with one of said arms and
leading to one side of the car, and a chain
connected to the other arm, leading to the op-
posite side of the car.
- 15 4. In a car-coupling, the combination of a
20 spring-cushioned draw-bar provided with a

beveled laterally-projecting draw-head and
with a longitudinal spline, a fixed block at-
tached to the car-body, provided with a bear-
ing for said draw-bar and with an arc-shaped 25
recess, in which said spline has a limited os-
cillating movement, a torsional spring con-
nected with said draw-bar, a sleeve on said
draw-bar provided with a longitudinal groove
for receiving said spline, arms attached to 30
said sleeve and projecting laterally therefrom
in opposite directions, a chain connected to
one of said arms and extending to one side of
the car and then to the top thereof, guides for
said chain, and a chain connected to the other 35
arm and extending to the opposite side of the
car.

GEORGE HARDY.
